Hanson and Hanson

UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

1,248,203.

Specification of Letters Patent. Patented Nov. 27, 1917.

Application filed May 16, 1917. Serial No. 168,967.

To all whom it may concern:

Be it known that I, GEORGE B. THOMAS, a citizen of the United States of America, and residing at Bridgeport, in the county of 5 Fairfield and State of Connecticut, have invented a certain new and Improved Electric Switch, of which the following is a specification.

My invention relates to electric switches 10 and particularly to switches of the three-point type, the object of my invention being to provide a switch of this type of simple and efficient construction which is more economical to manufacture than those of the 15 same type now on the market.

In the accompanying drawings,

Figure 1 is a plan of a switch in which my invention is embodied in one form;

Fig. 2 is a broken side elevation;

Fig. 3 is a schematic representation of 20 wiring connections and portions of the switch mechanism; and

Fig. 4 is a similar view of a modified construction.

The present switch embodies a modified construction for accomplishing the same purpose as that of the switch shown in the Bates application, Serial No. 157,695 and my co-pending application, Serial No. 30 168,658, and differs therefrom only in the construction of the switch bar and arrangement of the switch terminals, by which changes I am able to diminish the expense of manufacture without lessening the efficiency of the switch. The invention is here 35 illustrated in a switch of push button type mounted in a cup shaped insulating base 10, having at one corner a main line terminal standard 11 with binding screw 12 and base 40 lug 13. From the base of this standard, a conducting strap 14 leads the current to the switch frame 15 mounted within the chamber and carrying the switch mechanism. At 45 diagonally opposite corners of the switch chamber are arranged the branch line terminal standards 16 and 17, carrying binding screws 18 and 19 and switch terminals 20 and 21 respectively. The U-shaped switch bar 22 is struck from sheet metal and angled to 50 shape, one blade 23 of the bar being adapted to engage the terminal 20 in one position of the switch and the other blade 24 being adapted to engage the second branch terminal 21 in the opposite position of the switch.

55 The push buttons 25 engage a rocker bar 26

which operates the switch bar 22 with a snap action in a well understood manner which need not be explained in detail.

The operation of the switch is readily understood. Inasmuch as the switch frame 14 is constantly in circuit through the strap 14, the switch bar is constantly alive. In one position of the switch it establishes connection with the branch terminal 20 through blade 23. In the opposite position, it breaks this connection but establishes the connection between blade 24 and the second branch terminal 21. By this construction, I have eliminated not only one of the arms of the switch bar, but also one of the switch terminals, viz. that heretofore connected to the main wire terminal, the foot of the latter being merely extended for connection to the base flange of the switch frame.

In Fig. 4, I have shown a modified construction in which the branch terminal 27 is arranged on the same side of the switch chamber as the terminal 20, but at the opposite end of the chamber as before. By this construction the blade 24 of the switch bar 80 may be eliminated since the blade 23 that connects with the terminal 20 will, on moving out of engagement therewith, make contact with the terminal 27. The capacity of the switch is in no wise limited by this modification, since the full stroke of the switch bar is retained.

I claim as my invention:

1. In a three-point electric switch, a cup shaped insulating base, a switch mechanism arranged within the switch chamber thereof, a main line wire terminal arranged in said chamber and directly connected to the frame of the switch mechanism, a switch bar mounted in said frame in electrical connection therewith, in combination a pair of branch line connections having terminals arranged in said chamber and connected alternatively with said switch bar in the opposite positions of the switch.

2. In a three-point electric switch, a cup shaped insulating base, a switch mechanism within the chamber thereof and comprising a frame, a switch spindle journaled therein, and switch blade means carried by, and electrically connected to, said spindle, a main line terminal mounted on the base and electrically connected to said switch frame, together with a pair of branch line terminals arranged in said chamber and connected al-

ternatively with said switch blade means in the opposite positions of the switch.

3. In a three-point electric switch, a cup-shaped insulating base, a switch mechanism within the chamber thereof and comprising a frame, a switch spindle journaled therein, and switch blade means carried by, and electrically connected to, said spindle, a main line terminal mounted on the base and electrically connected to said switch frame, together with a pair of branch line terminals arranged in said chamber and connected alternatively with said switch blade means in the opposite positions of the switch, said branch line terminals lying at the same level 15 in the switch chamber on opposite sides of the axis of the switch spindle.

In testimony whereof I have signed my name to this specification.

GEORGE B. THOMAS.
